INVENTOR.

UNITED STATES PATENT OFFICE.

CALVIN P. WOLFE, OF MILWAUKEE, WISCONSIN, ASSIGNOR TO L. J. MUELLER FURNACE COMPANY, OF MILWAUKEE, WISCONSIN, A CORPORATION OF WISCONSIN.

REGISTER AND METHOD OF MANUFACTURING THE SAME.

Application filed February 20, 1922. Serial No. 538,139.

To all whom it may concern:

Be it known that I, CALVIN P. WOLFE, a citizen of the United States, and resident of Milwaukee, in the county of Milwaukee and 5 State of Wisconsin, have invented new and useful Improvements in Registers and Methods of Manufacturing the Same, of which the following is a description, reference being had to the accompanying drawings, which are a part of this specification.

This invention relates to improvements in registers and method of manufacturing the same, and more particularly to registers for pipeless furnaces.

15 Pipeless furnaces are usually connected directly to the floor above to a large register mounted in the floor and which register is usually formed with an outer cold air intake portion and an inner warm air outlet portion, the cold air intake opening usually surrounding the hot air outlet. The openings in the register are of lattice formation and include a ring-like flanged portion which separates the intake passageway from the 20 outlet passageway. Considerable trouble has been experienced in casting these registers due to the fact that portions of the metal in cooling after the casting operation contract unequally, with the result that the 25 ring-like portion as well as other parts crack and produce an imperfect casting which cannot be used.

It is one of the objects of the present invention to overcome the before mentioned 30 objectionable features and provide a register and method of manufacturing the same which will eliminate defective registers due to cracks forming in the casting process.

A further object of the invention is to provide a register and method of manufacturing the same in which the mold in which the registers are cast is adapted to separate portions of the metal at points of greatest strain and thus eliminate undue strains and cracking.

45 A further object of the invention is to provide a register and method of manufacturing the same which is simple and inexpensive to produce and is well adapted for the purpose described.

With the above and other objects in view, the invention consists of the improved register and method of manufacturing the same, and its parts and combinations as set forth 50 in the claims, and all equivalents thereof.

In the accompanying drawing in which the same reference characters indicate the same parts in all of the views:

Fig. 1 is a face view of the improved register;

Fig. 2 is a face view of a portion of the mold in which the register is cast showing dividing strips in position;

Fig. 3 is a vertical sectional view of portions of a mold taken on line 3—3 of Fig. 65 2; and

Fig. 4 is a sectional detail view of the register taken on a larger scale.

Referring to the drawing, the numeral 8 indicates the improved register which comprises the outer rectangular border or edge portion 9, the inner annular flange portion 10 which divides the register into a cold air inlet portion 11, and a warm air outlet portion 12. Said inlet and outlet portions 11 and 12 are formed, and the parts connected together by cross portions 13 of lattice formation.

The annular flange 10 is of considerable depth to permit the attachment of the inner 80 warm air pipe thereto, and in ordinary casting the flange would crack at a number of different places and these cracks would extend in use. To overcome this difficulty the mold 14 at a plurality of points is provided 85 with pairs of copper, bronze, or other like metal stop strips 15, which are positioned in the mold transversely of the mold groove 16 in which the flange 10 is formed. Said strips are substantially of the same depth 90 as the flanges so that when molten metal is poured into the mold through the ordinary openings (not shown) of the mold, the pairs of stop strips will prevent the flow of metal entirely around the annular flange 95 with the result that the annular flange is of segmental form and the segments 10' as well as other portions of the register may expand and contract without unduly straining the other parts.

100 By providing pairs of stop strips the end portions of the molten metal forming the segments will not fuse together even though they fuse with the respective pieces of each pair as said pieces will not fuse together.

105 After the casting operation the flange segments will shrink in cooling and the separated end portions will permit said shrinking without liability of cracking portions of the register.

When the casting is removed from the mold to be finished the stop strips are also removed or their edge portions are ground off so they will not show in the finished casting, and the straight equally spaced radial cuts will have the appearance of forming part of the design of the register.

From the foregoing description it will be seen that the register is of very simple 10 construction and the method of making same is likewise simple and well adapted for the purpose described.

What I claim as my invention is:

1. The method of manufacturing furnace 15 registers which consists in placing pairs of stop strips at a plurality of points in the casting mold to weld with the adjacent metal and divide portions of the register subjected to undue strain in shrinking during cooling of the molten metal forming the register.

2. The method of manufacturing furnace registers having a depending medial flange which consists in placing pairs of stop strips 25 of other material than the material of the casting at a plurality of points in the casting mold to weld with the adjacent metal and to divide portions of the medial flange subjected to undue strain in shrinking during cooling of the molten metal forming the register.

3. The method of manufacturing furnace registers having a depending medial annular flange which consists in placing pairs 35 of stop strips of other material than the material of the casting at a plurality of points in the casting mold to weld with the adjacent material and to divide portions of

the medial flange subjected to undue strain in shrinking during cooling of the molten metal forming the register, and then removing the stop strips from the flange. 40

4. A new article of manufacture, comprising a cast metal furnace register having outer and inner lattice work formation and a medial depending sectional rib, the adjacent end portions of said sectional rib having stop strips of other material than the material of the register welded to the said end portions and spaced apart a slight distance from each other. 45

5. A new article of manufacture, comprising a cast metal furnace register having outer and inner lattice work formation and a medial depending annular rib formed of segments, the adjacent end portions of the segments having stop strips of other material than the material of the register welded to the said end portions and spaced apart a slight distance from each other. 55

6. A new article of manufacture, comprising a cast metal furnace register having an outer border and a medial depending annular flange connected together by both outer and inner cross portions of lattice work formation, the annular flange being of segmental formation, the adjacent end portions of the segments having stop strips of other material than the material of the register welded to said end portions and spaced apart a slight distance from each other. 65

In testimony whereof, I affix my signature.

CALVIN P. WOLFE.
